UNITED STATES PATENT OFFICE.

PEIRCE VAN VLECK AND HOWARD COOPER, OF BALTIMORE, MARYLAND, ASSIGNEES
TO WILLIAM H. PEIRCE, OF BALTIMORE, MARYLAND.

COMPOUND ENGINE.

1,385,028.

Specification of Letters Patent. Patented July 19, 1921.

Application filed September 28, 1920. Serial No. 413,254.

To all whom it may concern:

Be it known that we, PEIRCE VAN VLECK and HOWARD COOPER, citizens of the United States, residing at Baltimore city, in the 5 State of Maryland, have invented certain new and useful Improvements in Compound Engines, of which the following is a specification.

This invention relates to engines and more 10 particularly to double acting cross compound expansion type.

The objects of the invention are:—

First, to construct an engine of the general class indicated, in which all valve gear 15 is eliminated and the valve distributing the fluid pressure on either side of the high and low pressure pistons is actuated by the same fluid reciprocating the pistons.

Second, to construct and arrange the 20 valve distributing the fluid pressure with respect to the chest and its relations to the high and low pressure cylinders, so that no stuffing boxes or glands are necessary for the elements connecting or controlling said 25 valve with the movements of the pistons.

Third, to construct and arrange ports in the distributing valve and chest in which 30 said valve reciprocates and oscillates, so that the motive fluid reciprocating the valve is efficiently and positively controlled, thereby insuring the constant and uniform operation of the motor or engine.

Fourth, to so construct and arrange the high and low pressure cylinders with a 35 head inclosing the chest and valve with coöperating ports, so that the engine can be cheaply manufactured and all the parts are readily accessible, easily and quickly assembled or taken apart and inspected or repaired with a minimum of cost and time 40 without breaking any actuating fluid connections.

Fifth, other advantages and objects of the invention will appear from the detailed 45 description of the construction and operation of the invention to be hereinafter given.

The invention consists of structural characteristics and relative arrangements of elements which will be hereinafter more fully 50 described and particularly pointed out in the appended claims.

In the drawings, in which similar reference characters indicate the same parts in the several figures,

Figure 1 is a longitudinal section partly 55 in elevation of the motor;

Fig. 2 is a section on line II—II of Fig. 1;

Fig. 3 is a section on line III—III of Fig. 1;

Fig. 4 is a section on line IV—IV of 60 Fig. 1;

Fig. 5 is a section on line V—V of Fig. 1;

Fig. 6 is a section on line VI—VI of Fig. 1;

Fig. 7 is a section on line VII—VII of 65 Fig. 1;

Fig. 8 is a section on line VIII—VIII of Fig. 1;

Fig. 9 is a section on line IX—IX of Fig. 1; 70

Fig. 10 is a section on line X—X of Fig. 1;

Fig. 11 is a section on line XI—XI of Fig. 1; 75

Fig. 12 is a section on line XII—XII of Fig. 1, and

Fig. 13 is a section on line XIII—XIII of Fig. 1;

Fig. 14 is a section similar to Fig. 1, 80 showing the position of valve and pistons for the return stroke.

Referring to the drawings, 10 is the high pressure cylinder and 11 the low pressure cylinder having reciprocating therein respectively, double acting pistons 12 and 13. 85 Piston 12 is connected to a tubular piston rod 14 passing through a stuffing box 15 while the low pressure piston 13 is provided with a rod 16 passing through a stuffing box 17, said rods 14 and 16 may be connected to any suitable pump, compressor or other mechanical expedient, not shown, and forming no part of the present invention, to which the power of the motor is to be applied. 90

The head 18 extending over the upper ends of the high and low pressure cylinders 10 and 11 is so cored, constructed and arranged as to form a chest 19 in which is provided a combined oscillatory and reciprocatory distribution piston valve 20 having end cylindrical sections 21 and 22, a central section 23, and smaller cylindrical sections 24 and 25 arranged between said sections 21, 22 and 23, as shown, said chest 100 95

19 being provided with the usual liner 26, and heads 27 and 28 secured in any well known manner and forming no part of the 105

present invention. In the head 18 are cored a series of ports 29, 30, 31, 32, 33, 33' and 34 below the chest 19 and ports 35 above the chest 19 as shown. Port 29 has branch 5 ports 36, 37, 38 and 39 which communicate with the interior of the chest 19 by means of openings 40, 41, 42 and 43 respectively, while port 33 is provided with branch ports 44, 45 and 46 which communicate with the 10 interior of chest 19 by means of openings 47, 48, and 49. Ports 30, 31, 32 and 33' communicate with the chest respectively by openings 50, 51, 52 and 53, and port 34 communicates with the interior of the chest 15 by opening 54 and with the upper port 35 by a branch port 55. Port 35 communicates with the opposite ends of the chest 19 by means of openings 56 and 57. Port 30 connects directly with one end of the high 20 pressure cylinder 10, while port 33' connects in a like manner with the upper end of the low pressure cylinder 11. 56, 57, 58 and 59 are ports cast in the high and low pressure cylinders and connect respectively 25 with the ports 29, 31, 32 and 34 in the head 18 for purposes to be presently described.

60 and 61 are by-pass ports or grooves at the ends of the low pressure cylinder to 30 permit the motive fluid pressure to pass around the piston 13 when the same over-travels said grooves.

The end cylindrical section 21 of the distribution valve 20 is provided with two short 35 longitudinal and peripheral ports 62 and 63 which are adapted to connect one end of the chest 19 respectively with the opening 40 of port 29 and opening 56 of port 35, while the ports 64 and 65 in the other end 40 cylindrical section 22 of valve 20 connect the other end of the chest 19, respectively with the openings 43 and 57 communicating with the ports 39 and 35, as will be readily seen from the drawings.

45 Passing through the cylindrical section 21 of the valve 19 with a tight fit is a pin 66, the outer end of which is suitably threaded, while its other or inner end is adapted to be firmly seated in a socket 67 formed in the cylindrical section 24 of valve 20, said pin 66 being slidably and loosely connected to the upper end of a rod 68 passing with considerable clearance through the port 30, as shown. The other end 69 of the rod 68 50 is adapted to pass within the hollow section of the high pressure piston rod 14 and its lower end 69 and enlarged upper end 70 are engaged by the under and upper sides respectively, of the tappet plate 71 secured to the upper side of high pressure piston 12, during the reciprocation of said piston 12, for the purpose of oscillating the valve 20 and thereby properly admit the live motive fluid or pressure to either end of the chest 55 19 or exhaust the entrapped motive fluid

therefrom to reciprocate said valve for purposes to be presently described.

The operation of the invention is as follows:

The parts being in the position as shown 70 in Fig. 1 the live motor fluid enters the port 56 and is conveyed by way of the port 29, branch port 38, opening 42 into the chest between the cylindrical sections 23, 24, of the valve 20 and passes through the opening 75 56 into the ports 31, 57, to the underside of the high pressure piston 12, and driving it upward as shown by the arrow. During this just described operation, the live motive fluid which had expanded during the 80 downward movement of the high pressure piston and was contained in the high pressure cylinder 10 above its piston 12, is passing out through port 30 and around the enlarged end 70 at the upper end of piston 85 rod 68 through the opening 50, into the chest 19 between the cylindrical sections 21, 24, of valve 20 through the opening 47 into branch port 44 and port 33 through branch 46 and opening 49 into chest 19 between cylindrical sections 22, 25, through opening 53 into port 33' to the upper side of the low pressure piston 13, whereby the intermediate pressure is applied to said low pressure piston and drives the same in a 95 downward direction, as indicated by the arrow, and the previously expanded intermediate motive fluid in the cylinder 11 on the underside of the piston 13 is forced out through ports 58, 32 opening 52 into chest 100 19 between cylindrical sections 23, 25 through opening 54 through ports 34 and 59 to the atmosphere or any suitable condenser if so desired.

As the live motive fluid port 29 has 105 branches 36 and 39 terminating in openings 40 and 43, through which high pressure can be admitted to the ends 21 and 22 of valve 20 through the high pressure grooves or ports 62 and 64, and the final exhaust port 110 34 through branch port 44 connects with the low pressure port 35 and to the ends 21 and 22 of the valve 20 through ports or grooves 63 and 65, consequently when the high pressure port or groove 62 registers with the 115 opening 40 and port 36 while the low pressure groove or port 65 and its co-operating opening 57 and port 35 at the opposite end of the valve 20 are in angular alignment, as shown in Figs. 2 and 13, a pressure differential is effected on the ends 21 and 22 which 120 firmly retains the valve 20 in the position shown in Fig. 1, and the other grooves or ports 63 and 64 and co-operating ports 35, 39 are out of angular alignment as clearly indicated in Figs. 2 and 13.

When the high pressure piston 12 reaches the end of its top stroke, the upper side of the projection or tappet plate 71 will engage the enlarged upper end 70 of the valve rod 130

68 and move the same upward through the port 30 and partially rotate the valve 20 through the pin connection 66, as will be readily understood. This partial rotation 5 of the valve 20 reverses the relationship of the grooves or ports 62, 64, 63 and 65, in the valve 20 and ports 36, 39 and 35 or openings 40, 43, 56 and 57, so that the high pressure valve port 64 registers with port 39 and 10 the live pressure valve port 63 registers with the port 35, which permits the motive fluid in the chest 19 between the cylindrical section 21 and head 27 to pass out through the opening 56, port 35, branch port 55, ports 15 34 and 59 to the atmosphere. This reverses the above referred to pressure differential and causes the valve 20 to move to the right as shown in Fig. 14, the pin 66 sliding through its bearing or opening in the upper 20 and enlarged end and owing to the low pressure ports or grooves 63, 65 being shorter than the high pressure ports or grooves 62, 64, the valve 20 is given a cushioning effect to its endwise travel by the cutting off of 25 the low pressure ports or grooves before the valve completes its longitudinal travel. Furthermore, the high pressure grooves or ports 62, 64, are slightly longer than the low pressure ports 63, 65, so that on partial 30 rotation or turning into alignment they will permit full opening of their port openings 40 and 43.

After the valve 20 has been shifted, as just described, to its right hand as shown in Fig. 35 14 and opposite position from that shown in Fig. 1, the opening 41 and branch port 37 of port 29 are in communication with the opening 50 and port 30 and hence live motive fluid is capable of passing into the top 40 of high pressure cylinder 10 and force the piston 12 downward. The expanded fluid from the underside of the piston 12 is then carried through the ports 57, 31, opening 51, chest 19, opening 47, branch port 44, port 45 45 33, branch port 45, opening 48, chest 19, opening 52 and ports 32 and 58, to the underside of the low pressure piston 13 and forcing it upward, while the expanded intermediate motive fluid in the upper end of the 50 low pressure cylinder 11 passes out through port 33', opening 53, chest 19, opening 54, ports 34 and 59 to the atmosphere or condenser. When the high pressure piston 12 reaches the end of its downward stroke, the 55 bottom on the lower end 69 of the valve rod 68 is engaged by the underside of the tappet plate 71 fixed to the piston 12 and said rod 68 is pulled down which in turn partially rotates the valve 20 to its first angular position, so registering its grooves or ports 62, 64, 63 and 65 as to admit the live fluid pressure to the outer end of the section 21 and force the valve to travel back to the position 60 shown in Fig. 1 and capable of repeating the 65 cycle of operations just described.

The grooves or ports 60 and 61 at the ends of the low pressure cylinder 11 have the function of by-passing the expanded motive fluid around the piston 13 when said piston overtravels said ports 60 and 61, the length 70 of said ports or grooves 60 and 61 being slightly greater than the width of the piston and hence assures a balance or equalizing of pressures on both sides of the piston and prevents the piston 13 from hitting the cylinder heads or ends in the event that the low pressure piston 13 completes its full stroke before the high pressure piston 12 has completed its stroke. 75

It will be seen that owing to the short 80 length of the ports 63 and 65, the openings 56 or 57 are cut off sufficiently early to effect a cushioning of the endwise travel or reciprocation of the valve 20, and the cushioning of the piston 12 is effected by providing that the movement of the valve 20 be such as to reverse or admit live motive fluid pressure in the high pressure cylinder 10 just before said piston 12 reaches the end of 85 its stroke. The valve 20 may also be so arranged to be completely balanced so far as circumferential pressures are concerned by arranging the ports in said valve in equal and opposite pairs and so disposed to communicate with the ports and openings in the 90 cylinders and chest thereby equalizing the pressure at all times on the opposite surface of the valve 20 and insuring it to easily and positively oscillate and reciprocate under all 95 conditions of service. 100

From the foregoing disclosure of the construction, arrangement, assembling and mode of operation of the motor, it will be seen that all the objects and advantages recited in the statement of invention are 105 fully and efficiently carried out and while one embodiment of such an arrangement is herein illustrated and described, it will be readily seen that many changes will readily suggest themselves to any one skilled in the 110 art without departing from the structural characteristics and relative arrangement of elements covered by the claims.

What we claim is:

1. A cross-compound engine comprising a 115 high pressure cylinder, a low pressure cylinder, a piston reciprocating within each of said high and low pressure cylinders, a live fluid pressure port and an exhaust port, ports leadings to the opposite ends of said high and low pressure cylinders, a chest having a series of openings communicating with the live fluid pressure and exhaust ports and ports leading to the opposite ends of said high and low pressure cylinders, a 120 combined oscillating and reciprocating distributing valve within said chest and having ports so constructed and arranged to cooperate with said series of openings communicating with the live fluid pressure and ex- 125 130

haust ports and ports leading to the opposite ends of said high and low pressure cylinders to admit live fluid pressure on opposite sides of the piston in the high pressure cylinder and direct the expanded fluid within said high pressure cylinder to the opposite sides of the piston within the low pressure cylinder and the expanded fluid within the low pressure cylinder to 5 the exhaust port and admit live fluid pressure within the chest and on each end of the distributing valve to reciprocate the same and exhaust said fluid from the chest, and means actuated by the reciprocating of a 10 piston for oscillating said reciprocating distribution valve.

2. A cross-compound engine comprising a high pressure cylinder, a low pressure cylinder, a piston reciprocating within each 20 of said high and low pressure cylinders, a live fluid pressure port and an exhaust port, ports leading to the opposite ends of said high and low pressure cylinders, a chest having a series of openings communicating 25 with the live fluid pressure and exhaust ports and ports leading to the opposite ends of said high and low pressure cylinders, a combined oscillating and reciprocating distributing valve within said chest and having 30 ports so constructed and arranged to co-operate with said series of openings communicating with the live fluid pressure and exhaust ports and ports leading to the opposite ends of said high and low pressure 35 cylinders to admit live fluid pressure on opposite sides of the piston in the high pressure cylinder and direct the expanded fluid within said high pressure cylinder to the opposite sides of the piston within the 40 low pressure cylinder and the expanded fluid within the low pressure cylinder to the exhaust port and admit live fluid pressure within the chest and on each end of the distributing valve to reciprocate the 45 same and exhaust said fluid from the chest, and means actuated by the reciprocating of a piston and freely passing through one of the ports leading into the cylinders for oscillating said reciprocating distribution 50 valve.

3. A cross-compound engine comprising a high pressure cylinder, a low pressure cylinder, a piston reciprocating within each of 55 said high and low pressure cylinders, a live fluid pressure port and an exhaust port, ports leading to the opposite ends of said high and low pressure cylinders, a chest having a series of openings communicating with the live fluid pressure and exhaust ports 60 and ports leading to the opposite ends of said high and low pressure cylinders, a combined oscillating and reciprocating distributing valve within said chest and having ports so constructed and arranged to co-operate with said series of openings com-

municating with the live fluid pressure and exhaust ports and ports leading to the opposite ends of said high and low pressure cylinders to admit live fluid pressure on opposite sides of the piston in the high pressure cylinder and direct the expanded fluid within said high pressure cylinder to the opposite sides of the piston within the low pressure cylinder and the expanded fluid 70 within the low pressure cylinder to the exhaust port and admit live fluid pressure within the chest and on each end of the distributing valve to reciprocate the same and exhaust said fluid from the chest, and a valve rod actuated by the reciprocating of 75 a piston and freely passing through one of the ports leading into the cylinders for oscillating said reciprocating distribution valve.

4. A cross-compound engine comprising a high pressure cylinder, a low pressure cylinder, a piston reciprocating within each of 80 said high and low pressure cylinders, a live fluid pressure port and an exhaust port, ports leading to the opposite ends of said high and low pressure cylinders, a chest having a series of openings communicating 85 with the live fluid pressure and exhaust ports and ports leading to the opposite ends of said high and low pressure cylinders, a combined oscillating and reciprocating distributing valve within said chest and having 90 ports so constructed and arranged to co-operate with said series of openings communicating with the live fluid pressure and 95 exhaust ports and ports leading to the opposite ends of said high and low pressure cylinders, a 100 combined oscillating and reciprocating distributing valve within said chest and having ports so constructed and arranged to communicate with the live fluid pressure and 105 exhaust ports and ports leading to the opposite ends of said high and low pressure cylinders to admit live fluid pressure on opposite sides of the piston in the high pressure cylinder and direct the expanded fluid 110 within said high pressure cylinder to the opposite sides of the piston within the low pressure cylinder and the expanded fluid within the low pressure cylinder to the exhaust port and admit live fluid pressure 115 within the chest and on each end of the distributing valve to reciprocate the same and exhaust said fluid from the chest, a pin attached to the valve and arranged parallel to the longitudinal axis of said valve, and a valve rod having one of its ends slidingly connected to said pin and actuated by the reciprocating of a piston for oscillating said reciprocating distribution valve.

5. A cross-compound engine comprising a high pressure cylinder, a low pressure cylinder, a piston reciprocating within each of 120 said high and low pressure cylinders, a live fluid pressure port and an exhaust port, ports leading to the opposite ends of said high and low pressure cylinders, a chest having a series of openings communicating 125 with the live fluid pressure and exhaust ports and ports leading to the opposite ends of said high and low pressure cylinders, a 130

- combined oscillating and reciprocating distributing valve within said chest and having ports so constructed and arranged to cooperate with said series of openings communicating with the live fluid pressure and exhaust ports and ports leading to the opposite ends of said high and low pressure cylinders to admit live fluid pressure on opposite sides of the piston in the high pressure cylinder and direct the expanded fluid within said high pressure cylinder to the opposite sides of the piston within the low pressure cylinder and the expanded fluid within the low pressure cylinder to the exhaust port and admit live fluid pressure within the chest and on each end of the distributing valve to reciprocate the same and exhaust said fluid from the chest, a pin attached to the valve and arranged parallel and to one side of the longitudinal axis of said valve and a valve rod having one of its ends slidably connected to said pin and freely passing through one of the ports leading into the cylinders and intermittently actuated by the reciprocating of a piston for oscillating said reciprocating distributing valve.
6. A cross-compound engine comprising a high pressure cylinder, a low pressure cylinder, a piston reciprocating within each of said high and low pressure cylinders, a live fluid pressure port and an exhaust port, ports leading to the opposite ends of said high and low pressure cylinders, a chest having a series of openings communicating with the live fluid pressure and exhaust ports and ports leading to the opposite ends of said high and low pressure cylinders, a single combined oscillating and reciprocating distributing valve within said chest and having ports so constructed and arranged to cooperate with said series of openings communicating with the live fluid pressure and exhaust ports and ports leading to the opposite ends of said high and low pressure cylinders to admit live fluid pressure on opposite sides of the piston in the high pressure cylinder and direct the expanded fluid within said high pressure cylinder to the opposite sides of the piston within the low pressure cylinder and the expanded fluid within the low pressure cylinder to the exhaust port and admit live fluid pressure within the chest and on each end of the distributing valve to reciprocate the same and exhaust said fluid from the chest, a pin attached to the valve and arranged parallel and to one side of the longitudinal axis of said valve, and a valve rod having one of its ends slidably connected to said pin and freely passing through one of the ports leading into the high pressure cylinder and its other end within the high pressure cylinder intermittently engaged and actuated by the reciprocation of the piston within the high pressure cylinder for oscillating said reciprocating distribution valve.

In testimony whereof we affix our signatures.

PEIRCE VAN VLECK.
HOWARD COOPER.
